UNITED STATES PATENT OFFICE.

RAYMOND G. F. LOEWY, OF JACKSON HEIGHTS, NEW YORK.

DESIGN FOR A LAMP.

Application filed July 9, 1928. Serial No. 27,420. Term of patent 7 years.

To all whom it may concern:

Be it known that I, RAYMOND G. F. LOEWY, a citizen of the Republic of France, residing at Jackson Heights, Long Island, county of Queens, and State of New York, have invented a new, original, and ornamental Design for a Lamp, of which the following is a specification, reference being had to the accompanying drawing, forming part thereof.

The figure of my design is an elevation.

In the drawing, the shading on the vertical rods represents glass.

I claim:

The ornamental design for a lamp as shown and described.

In testimony whereof I have affixed my signature to this specification.

RAYMOND G. F. LOEWY.
